UNITED STATES PATENT OFFICE.

FRITZ REICHENBACH, OF CHARLOTTENBURG, GERMANY.

FLY-WHEEL FOR QUICK-RUNNING INTERNAL-COMBUSTION ENGINES.

SPECIFICATION forming part of Letters Patent No. 757,636, dated April 19, 1904.

Application filed June 19, 1903. Serial No. 162,274. (No model.)

To all whom it may concern:

Be it known that I, FRITZ REICHENBACH, civil engineer, a subject of the King of Prussia, German Emperor, residing at No. 14 Bismarckstrasse, Charlottenburg, in the Kingdom of Prussia, German Empire, have invented a new and Improved Fly-Wheel for Quick-Running Internal-Combustion Engines, of which the following is a specification.

This invention relates in general to internal-combustion engines in which the charge is ignited by electric sparks, and in particular to a combination of the means for producing the sparks with the fly-wheel of the engine or, more precisely, to the combination of the latter with the magnet of the electric inductor, the object being to reduce the weight of the engine by making said magnet a part of the fly-wheel.

A preferred form of construction of my invention is illustrated in the accompanying drawings, in which—

Figure 1 is a vertical sectional view taken on the line I I of Fig. 2, and Fig. 2 a vertical sectional view taken on the line II II of Fig. 1, the engine being shown in side elevation.

The fly-wheel consists in the example shown of a disk *b*, manufactured of non-magnetic material—such, for instance, as brass or bronze or the like—the tire of the wheel being formed by a permanent magnet *c*, the main part of which is circularly bent, so as to correspond to the circular shape of the disk *b*, whereas the ends *c' c'* are bent inward to form the concentric poles *c' c'*, one pole being located diametrically opposite the other. The length of the legs of the magnet measured from the neutral line *i i* to the commencement of the pole-pieces *c' c'* is obviously very great, which is highly favorable for the intensity and long effectiveness of the magnet, and thus of the whole inductor. The magnet is shown in the drawings as formed of three sections of corresponding shape, each section being an independent magnet. It is obvious, however, that it may be formed of only one section or magnet.

The disk *b* is rigidly secured to the drive-shaft by any suitable means, a key being

shown in the drawings for this purpose. The magnet may be secured to the disk in any suitable manner, preferably by clamping-bolts *b'*, as shown in the drawings.

The armature *a* of the inductor is surrounded by a bobbin *d*. This armature is stationary supported concentric with the drive-shaft *g* and between the poles of the magnet by means of a post *a'*, the shaft passing loosely through the center of the armature. The electric current is generated, as is well known, by constantly changing the excitation of the armature *a* by means of poles *c' c'* of the magnet.

The poles of the igniter device *h* are in circuit with the bobbin *d* by means of the wires *e f*. The driving-shaft is connected by the pitman *k* to the piston *j* and is driven through the pitman *k* by the piston *j* in the usual manner.

It is obvious that the disk *b* may be replaced by a wheel proper having the usual spokes, the magnet also forming in this instance the tire of the wheel, and thus converting the same into a fly-wheel.

It is a matter of course that the disk *b* may be replaced by a wheel proper having spokes as usual, the magnet forming then also in this instance the tire of the wheel, turning the same thus into a fly-wheel.

Having now described my invention, what I desire to secure by a patent of the United States is—

1. In a quick-running internal-combustion engine, the combination with the engine-shaft and the means for rotating it, of a fly-wheel consisting of non-magnetic material; a magnet fixed to said fly-wheel and adapted to form the tire of the same; a stationary armature adapted to be excited by the poles of said magnet; a bobbin surrounding said armature, and means for utilizing the currents generated in said bobbin for igniting the explosive mixture required for driving the said fly-wheel with its magnet, as set forth.

2. In a quick-running internal-combustion engine, the combination with the engine-shaft and the means for rotating it, of a fly-wheel consisting of non-magnetic material; a circular permanent magnet fixed to said fly-wheel and adapted to form the tire of the same; a stationary armature embraced by said magnet.

and adapted to be excited by the poles of the same; a bobbin surrounding said armature, and means for utilizing the currents generated in said bobbin for igniting the explosive mixture required for driving the said fly-wheel with its magnet, as set forth.

3. In a quick-running internal-combustion engine, the combination with the engine-shaft and the means for rotating it, of a fly-wheel consisting of non-magnetic material; a circular permanent magnet fixed to said fly-wheel and adapted to form the tire of the same and having its pole-pieces formed by bent-up portions embraced by its legs; a stationary armature embraced by said magnet and adapted to be excited by the poles of the same; a bobbin surrounding said armature, and means for utilizing the currents generated in said bobbin for igniting the explosive mixture required for driving the said fly-wheel with its magnet, as set forth.

4. In a quick-running internal-combustion engine the combination, with the engine-shaft and the means for rotating it, of a fly-wheel, a magnet fixed thereto, a stationary armature, a bobbin surrounding said armature whereby the rotation of the fly-wheel will generate an electric current in said bobbin, and means for

utilizing the currents thus generated for igniting the explosive mixture in the engine-cylinder.

5. In a quick-running internal-combustion engine the combination, of a fly-wheel, a circular permanent magnet fixed thereto, a stationary armature embraced by said magnet and adapted to be excited by the poles of the same, a bobbin surrounding said armature whereby the rotation of the magnet will generate an electric current in said bobbin and means for utilizing the current thus generated for igniting the explosive mixture.

6. In an internal-combustion engine the combination of the engine-shaft, a circular permanent magnet carried thereby, a stationary armature embraced by said magnet and adapted to be excited by the poles of the same, a bobbin surrounding said armature, and means for utilizing the current generated in said bobbin for igniting the explosive mixture.

In witness whereof I have hereunto set my hand in presence of two witnesses.

FRITZ REICHENBACH.
